Primary Examiner—Alan P. Douglas*Assistant Examiner*—Cathron B. Matta*Attorney, Agent, or Firm*—Peterson, Wicks, Nemer & Kamrath[57] CLAIM

The ornamental design for a memorial flower vase holder, as shown and described.

DESCRIPTION

FIG. 1 is a right rear perspective view of a memorial flower vase holder embodying my new design;
FIG. 2 is a left end elevational view thereof, with the right end being a mirror image thereof;
FIG. 3 is a top plan view thereof;
FIG. 4 is a bottom plan view thereof;
FIG. 5 is a front elevation thereof; and,
FIG. 6 is a rear elevation thereof.
